UNITED STATES PATENT OFFICE.

JOHN J. CANNAN, OF ROCHESTER, NEW YORK.

HAT-HOLDER.

SPECIFICATION forming part of Letters Patent No. 659,363, dated October 9, 1900.

Application filed February 6, 1900. Serial No. 4,210. (No model.)

To all whom it may concern:

Be it known that I, JOHN J. CANNAN, of Rochester, in the county of Monroe and State of New York, have invented certain new and useful Improvements in Hat-Holders; and I do hereby declare the following to be a full, clear, and exact description of the same, reference being had to the accompanying drawings, forming a part of this specification, and to the reference-numerals marked thereon.

My present invention has for its object to provide a holder adapted particularly to be applied to hat-boxes, cases, or to trunks for supporting silk hats and preventing injury thereto, although equally well adapted to hold other styles and adjustable to accommodate various sizes thereof, and which may, if desired, be moved out of operative position when not in use, allowing the box or case to be used for other purposes.

To these ends the invention consists in certain improvements in construction and combinations of parts, all as will be hereinafter described, the novel features being pointed out in the claims at the end of this specification.

In the drawings, Figure 1 is a perspective view of a case, partly in section, showing the operation of a holder constructed according to my invention; Fig. 2, a side elevation, partly in section, of one of the holders; Fig. 3, a top plan view of the same; Fig. 4, a view similar to Fig. 2, showing a modification; Fig. 5, a sectional view on the line 5-5 of Fig. 3.

Similar reference-numerals in the different figures indicate similar parts.

Hat-holders constructed in accordance with my invention support the hat at each end by engaging the brim close to the crown, where it is the stiffest, and I have shown in the drawings an ordinary form of case 1, adapted to contain a single hat 2. The holders embody a base 3, having the lower and normally-stationary arm 4, provided with the broad curved plate 5 on its extremity, upon which the brim 6 of the hat rests, and the movable arm 7, arranged above the former, pivoted to the base at 8 and having the plate 9, adapted to coöperate with the plate 5 to engage the upper side of the brim. Both of these plates 5 and 9 are provided with a cov-

ering 10, of plush or velvet or other soft material or padding, the lower stationary plate being inclined somewhat at an angle and the upper one 5 being loosely connected to the arm 7 by a pin 11, passing through ears or lugs 12 and the ear 13 on the plate. The ear 13 is tapered slightly toward its upper edge and fitting loosely between the former allows the plate to tilt, fitting closely upon the hat-brim at whatever angle the latter may be. In the rear of the pivot 8 the upper arm 7 is provided with an angular face or cam-surface 14, against which bears a spring 15, rigidly connected at its lower end to the base 3. This construction permits the upper arms to be turned upon their pivots into a vertical position when it is desired to insert or remove the hat, and the springs bearing against the faces 14 hold the arms firmly in operative position upon the hat-brim when they are closed.

If the holders are to be used in single-hat cases, they may be secured to the sides of the case by means of a bolt 16 and thumb-screw 17, as shown particularly in Fig. 5. Any lateral adjustment that is necessary to accommodate hats of various sizes may be permitted by forming horizontal slots in the side of the casing through which the screws 17 are passed, as will be understood.

18 indicates a point or stud formed on the rear side of the base 3 of the holder just described, adapted to engage the casing and assist in securing the holder, preventing rotary movement thereof.

Another form of the device and one which is intended more particularly to be used in hat-boxes in trunks or similar places which it is often desirable to use for other purposes consists of an addition to the holder heretofore described whereby the gripping-arms may be folded out of the way and toward the side of the receptacle when not in use.

20 indicates a base-plate rigidly connected to one of the sides of the receptacle by screws 21 and having lugs or brackets 22, upon which is pivoted the base 3' by means of similar brackets 23, overlapping the former. A small rod 24, extending through all four of the brackets, forms the pivot, and wound thereon is a coiled spring 25, one end of which is attached to the swinging base 3' and the other to the

stationary base 20. The tension of the spring is increased when the arms are revolved to the side of the receptacle, as shown in dotted lines in Fig. 3, and serves to return them to the normal projecting position. An adjustable screw 26, threaded into one side of the base 3' and operating against a post 27, forms an adjustable stop for limiting the outward movement of the arms, permitting their adjustment for hats of various sizes. Arranged upon the inner surface of the base-plate 20 and projecting slightly above the top thereof is a small leaf-spring 28, forming a catch adapted to engage in a notch 29, formed in the side of the upper lug 23, to hold the arms when rotated toward the side against the tension of the spring 25. By a slight pressure of the finger against the projecting end of the spring-catch the frame will be released and the engaging arms moved into the normal position by the spring 25.

I have shown the holders engaging the opposite ends of the hat attached to opposite sides of the case or receptacle, as in this way a single style of holder operating in one direction may be utilized; but it will be readily understood that they might be made to turn in opposite directions and both applied to the same side of the case, one folding over the other when not in use.

Holders such as I have described are simple in construction and operation. The broad padded supporting-plates upon the lower stationary arms engaging the brim at the ends of the hat close to the crown and the spring-operated arms having the coöperating padded plates resting upon the upper side of the brim hold the hat firmly, preventing any abrasion or other injury to its surface. The devices may be applied to the trays of sample-hat trunks, and by reason of their compactness the space may be greatly economized—as, for instance, hats with rounding crowns may be arranged to rest one in the other and each supported upon a separate pair of holders, or in carrying ladies' hats they may be supported separately and prevented from contact either with the surrounding casing or adjacent articles.

50. I claim as my invention—

1. In a hat-holder, the combination with a base, the stationary arms thereon having the narrow plates upon their extremities adapted to support the hat-brim at its ends, of the movable arms pivoted to the base and having the narrow plates upon their outer ends adapted to engage the brim directly opposite the supporting-plates, the shoulders on the arms in rear of the pivots, and the springs operating against the shoulders to hold the arms in the operative position.

2. In a hat-holder, the combination with a base-plate adapted to be mounted upon a stationary support, of the holding-arms relatively movable toward and from each other, pivotally connected to the base to swing together thereon, means for arranging the arms,

and a stop for limiting their outward movement.

3. In a hat-holder, the combination with a base-plate mounted upon a stationary support, of a plate pivoted to the support to turn thereon having the stationary arm and the coöperating movable arm, means for turning the plate on its pivot with the arms extended, and an adjustable stop for limiting its outward movements.

4. In a hat-holder, the combination with a base-plate, the coöperating arms having the narrow plates thereon adapted to engage upon the opposite sides of a hat-brim, said arms being connected upon their inner ends, of a pivotal connection between the arms and the base, a stop for limiting their outward movement, and a catch for retaining the arms when moved out of operative position.

5. In a hat-holder, the combination with a base-plate, the arms engaging opposite sides of the hat-brim and connected upon the ends, of the pivotal connection between the arms and the base, a spring-catch for retaining the arms when the latter have been moved out of operative position, spring connections for extending the arms when the catch is released, and an adjustable stop for limiting their outward movement.

6. In a hat-holder, the combination with a base having the stationary arm provided with a hat-support, a movable arm coöperating with the support, and means for holding the latter in operative position, of a stationary support, a pivotal connection between the support and the base, means for holding the arms extended, a stop for limiting their outward movement, and a retaining device operating to hold the arms when moved out of operative position.

7. In a device for holding hats adapted to support a hat by engaging its brim at opposite ends, the combination with a support having the brackets, of the base having the engaging arms, and the brackets pivotally connected to the support, the spring-catch on the latter engaging the base to retain the arms when moved out of the operative position, a yielding connection between the base and support holding the arms in operative position, and an adjustable stop for limiting their movement in one direction.

8. In a hat-holder, the combination with a base having the stationary arm provided with a hat-support, a movable arm pivoted to the base and coöperating with the support, the shoulder on the end of said arm, and the spring attached to the base and bearing thereon, of the stationary support, pivotal connections between it and the base, a spring-catch for retaining the arms when moved out of the operative position, spring connections between the support and the base for returning the latter to the normal position, and an adjustable stop for limiting the outward movement of the arms.

9. In a hat-holder, the combination with the

base, of a stationary arm thereon having the narrow plate at its end, of the movable arm pivoted on the base, and a narrow plate loosely pivoted on said arm and adapted to engage upon opposite sides of the hat-brim to clamp the latter between them.

10. The combination with a stationary support, of two holders for coöperating with a hat-brim upon opposite sides of the crown, each embodying a stationary arm, having a narrow plate at its end, arranged at an angle to said arm for engaging flatly against one side of the hat-brim, and a movable arm having a correspondingly-narrow plate loosely mounted upon its end and adapted to engage the other side of the hat-brim.

11. The combination with a stationary support, of two holders for coöperating with opposite ends of a hat, each embodying a stationary arm mounted upon a base secured to the support, and a narrow plate thereon for engaging one side of a hat-brim, and a movable arm pivoted to said base and having the loosely-pivoted plate thereon for coöperating 25 with the other side of the brim, and means for pressing the arms together.

12. In a hat-holder, the combination with the stationary arm mounted upon a base having the narrow plate at its end adapted to engage a hat-brim, of a movable opposing arm pivoted to said base having a narrow plate adapted to engage the opposite side of a hat-brim, one of said plates being inclined and the other having a pivotal connection with 35 its arm whereby it may engage flatly against the brim, and means for holding the plates together with a hat-brim between them.

13. In a hat-holder, the combination with a support, the relatively-movable arms connected to a base and mounted on the support, each having the narrow curved plates at their ends for engaging opposite sides of a hat-brim, one of said plates being slightly inclined and the other movable relative its 45 supporting-arm to engage flatly against the

brim, and means for holding the arms in engagement with opposite sides of a hat-brim.

14. The combination with a stationary support, of the arms thereon adapted to engage one side of a hat-brim upon opposite sides of the crown, engaging members resting upon the opposite side of the brim above the stationary arms, movable connections between the members upon one side of the hat-brim and the support, and means upon the latter 55 for holding said members in engagement with the hat-brim.

15. The combination with a stationary support or receptacle having the elongated apertures in its sides, the holders arranged upon 60 opposite sides of the crown of the hat embodying a base provided with the stationary arm having the narrow plate at its end, the movable arm pivoted on the base, and the narrow plate loosely mounted on said arm 65 coöperating with the former plate to engage a hat-brim between them, of the bolts extending through the aperture and engaging each holder, whereby the latter may be adjusted relatively.

16. In a hat-receptacle having the elongated apertures in its sides, the combination with a hat-holder adapted to be arranged upon opposite sides of the crown of the hat embodying a base-plate, coöperating arms 75 having the narrow plates thereon adapted to engage upon the opposite sides of a hat-brim connected together upon their inner ends, pivoted connections between the arms and the base, and a stop for limiting their outward movement, of a bolt extending through the aperture and engaging the base of each holder and permitting the latter to be adjusted relatively to support hats of various sizes.
